EYEGLASS FRAME OR THE LIKE

Alexander Kono, Woodside, N.Y., assignor to Kono Manufacturing Co. Inc., Woodside, N.Y., a corporation of New York

Filed Aug. 3, 1964, Ser. No. 31,123

Term of patent 14 years

(Cl. D57—1)

FIG. 1 is a front elevational view of an eyeglass frame or the like, showing my new design;

FIG. 2 is a top plan view thereof; and

FIG. 3 is a side view thereof.

The drawing is shaded in FIGS. 1 and 3 to show contrast.

I claim:

The ornamental design for an eyeglass frame or the like, substantially as shown and described.
